UNITED STATES PATENT OFFICE.

JOHN F. GALVIN AND WILLIAM B. KOCHNER, OF ST. LOUIS, MISSOURI, ASSIGNEES TO
GALVIN ELECTRIC MANUFACTURING COMPANY, OF ST. LOUIS, MISSOURI, A COR-
PORATION OF MISSOURI.

FAN-OSCILLATING MECHANISM.

Application filed July 16, 1925. Serial No. 43,925.

This invention pertains to fan oscillating mechanism such as is used in small ventilating fans to vary the direction of the delivery of air while the fan is running.

5 In such a mechanism it is desirable to be able to vary the extent of the swing of the fan, and it is further desirable to be able to make the adjustment therefor while the fan is running. In the usual practice the arrangements for adjusting the throw of the fan are located beneath the motor frame, usually under the motor bearing and adjacent the moving connections between the oscillating mechanism and the fan base. Such an arrangement is objectionable on account of the fact that the mechanism is usually provided with lubricating devices containing oil or grease and, since the manipulative parts for adjustment are below, there is often a leakage of oil or grease which covers these parts so as to soil the fingers when handling. With this location of manipulative parts there is furthermore danger of injury to the fingers on account of the proximity of moving connections.

One of the objects of this invention, therefore, is to provide oscillating mechanism which may be adjusted while the fan is running but in which danger of soiling or 30 injuring the fingers is obviated.

Another object is to provide novel and improved means for adjusting the throw of the fan.

Further objects will appear from the following description taken in connection with the accompanying drawing, in which:

Figure 1 is a sectional view of fan oscillating mechanism embodying this invention, taken on line 1—1, Figure 3;

40 Figure 2 is an end view of the same taken on line 2—2, Figure 4;

Figure 3 is a section on line 3—3, Figure 1; and

45 Figure 4 is a bottom view of the adjusting head.

Referring to the drawing 1 designates the frame of the fan motor. This may be mounted for swinging movement as by swiveling on a shank 2 working in a stationary base 3 in any well known manner. The motor shaft works in a bearing 4 and may be provided with a rear extension 5 having a worm 6 engaging a worm wheel 7

on a transverse shaft 8 carrying a second worm 9 engaging a second worm wheel 10 55 fixed to a hollow vertical shaft 11. These parts may be enclosed in a housing 12 having a vertical bearing 13 in which the shaft 11 moves. The housing 12 is adapted to receive oil or grease for lubricating the contained mechanism, and may be provided with a suitable cover 14 fixed in place by a screw 15.

The shaft 11 carries at its lower end a head 16 recessed to receive an adjusting 65 plate 17. The plate 17 is not fixed to the shaft 11 but to a stem 18 passing upwardly through the hollow shaft 11 and through the cap 14 to the outside of the housing above the same where it is equipped with a manipulative button 19. By turning the button 19 and the stem 18 fixed thereto and extending downwardly to the plate 17 to which it is also fixed, the plate 17 will be turned for adjusting the crank as will be described 70 75 presently.

Mounted on the head 16 and in engagement with the plate 17 is a carrier 20. This carrier is pivoted at 21 to the head 16 and is provided with a radial slot 22 adapted to 80 be engaged by a pin 23 fixed to and projecting downwardly from the plate 17. By means of this pin and slot connection, the carrier 20 may be moved from side to side by properly rotating the plate 17 by manipulation of the spindle 18. The carrier 20 and the plate 17 are held in place by a cap 24 fixed to the head 16, as by a pin 25, and provided with a curved slot 26 in which a crank pin 27 mounted on the carrier 20 may 90 move when the carrier swings on its pivot 21. It will be seen, therefore, that by manipulation of the button 19, the carrier 20 may be swung back and forth from side to side on the head 16. The crank pin 27 is 95 mounted on one side of the carrier so that movement of said carrier to one side will move the crank pin out to the extreme rim of the head 16 while movement in the opposite direction will bring the crank pin substantially into alignment with the shaft 11. It will be seen, therefore, that this carrier and its pin 27 provide a crank of variable throw according to the adjustment of the plate 17.

100 105 The crank pin 27 may be connected by a

2
suitable link 28 with a fixed pivot 29 on the base 3 so that rotation of the shaft 11 will operate to swing the fan from side to side through an arc depending on the adjustment of the crank pin 27. A detent 30 engaging suitable notches in the plate 17 is adapted to yieldingly retain said plate in adjusted position.

In the operation of this device the motor, through the agency of the gearing 6, 7, 8, 9 and 10, drives the vertical shaft 11 and thereby the head 16 in rotation. Said rotation will carry the crank pin 27 in a circular path so as to swing the fan back and forth. Since the rotation of the shaft 11 is quite slow on account of the large reduction ratio of the gearing 6, 7, 8, 9 and 10, the rotation of the manipulative button 19 will also be slow so that the button may be grasped and turned in either direction relatively to the shaft 11 even while the fan is in motion. Said movement of the button 19 will have the effect, as above described of changing the length of the crank arm. Since the path of the pin 27 across the head 16 passes through the center of said head, the pin 27 may be adjusted so as to position it at the center and when so positioned, the fan will not oscillate.

30 It will be seen, therefore, that in accordance with this invention oscillating mechanism is provided in which the manipulating adjusting element is placed above the head and even above the motor bearing. There is thus no danger of soiling or injuring the fingers during said manipulation.

It is obvious that various changes may be made in details of construction without departing from the spirit of this invention; it is, therefore, to be understood that this invention is not to be limited to the specific details shown and described.

Having thus described the invention, what is claimed is:

45 1. In a fan having a base and a motor thereon, oscillating mechanism comprising, a head connected to be driven by the motor, a crank mounted for adjustment on said head, an element mounted on said head and having an adjusting connection with said crank, and a manipulative member having a stem extending downwardly toward and connected to operate said element.

2. In a fan having a base and a motor thereon, oscillating mechanism comprising, a head connected to be driven by the motor, a crank mounted for adjustment on said head, and means for adjusting said crank and having a manipulative element located above said head.

3. In a fan having a base, a motor thereon provided with a shaft and a bearing for said shaft, oscillating mechanism comprising a head connected to be driven by the motor shaft, a crank mounted for adjustment

on said head, and means for adjusting said crank having a manipulative element above the bearing.

4. Fan oscillating mechanism, comprising, a shaft driven by the fan motor, a rotating head driven by said shaft, a carrier adjustable transversely of said head and providing a crank connected with a stationary anchor, a rotatable adjusting plate for adjusting said carrier to vary the throw of said crank, and a stem connected for adjusting said plate and having a manipulative element at the upper end thereof.

5. A fan oscillating mechanism, comprising, a vertical shaft driven by the fan motor, a rotating head driven by said shaft, a carrier pivoted on said head and carrying a crank pin, an adjusting element movable concentrically with said shaft and connected to move said carrier, a stem within said shaft and fixed to said element, and a manipulating member at the top of said stem.

6. A fan comprising, a base, a motor frame provided with a motor and mounted to oscillate on said base, reducing gearing mounted on said frame and connected to be driven by said motor, a crank connected with said base, a sleeve connecting said gearing and said crank to drive the latter, and means for adjusting said crank including a stem in said sleeve and a manipulative element located away from said crank in order that it may be manually adjusted without injury.

7. A fan comprising, a base, a motor frame provided with a motor and mounted to oscillate on said base, reducing gearing mounted on said frame and connected to be driven by said motor, a crank connected with said base, a sleeve connecting said gearing and said crank to drive the latter, and means for adjusting said crank including a stem in said sleeve and a manipulative element located above said gearing, substantially as and for the purpose set forth.

8. Fan oscillating mechanism comprising, a shaft driven by the fan motor, a rotating head driven by said shaft, a carrier adjustable transversely of said head and providing a crank connected with a stationary anchor, a rotatable adjusting plate for adjusting said carrier to vary the throw of said crank, a stem within said shaft connected for adjusting said plate, a casing enclosing said head, shaft and carrier and a manipulative element on said stem above said casing.

9. A fan comprising, a base, a motor frame provided with a motor and mounted to oscillate on said base, reducing gearing mounted on said frame and connected to be driven by said motor, a crank driven by said gearing and connected with said base, mechanism for shifting said crank while maintaining its operative connection to vary its throw, and a manipulative element for mov-

ing said shifting means while the crank is in motion, said manipulative element being located away from said crank in order that it may be manually adjusted without injury.

- 5 10. A fan comprising, a base, a motor frame provided with a motor and mounted to oscillate on said base, reducing gearing mounted on said frame and connected to be driven by said motor, a crank driven by said 10 gearing and connected with said base, mechanism permitting continuous shifting of said

crank, while maintaining its operative connection to vary its throw, and a manipulative element for moving said shifting means while the crank is in motion, said manipulative element being located above said gearing substantially as and for the purpose set forth.

In testimony whereof we affix our signatures this 17th day of June, 1925.

JOHN F. GALVIN.

WILLIAM B. KOCHNER.
